UNITED STATES PATENT OFFICE.

CLARENCE E. GOHEEN, OF SOUTH BEND, INDIANA.

AUTOMOBILE SIGNAL.

Application filed November 21, 1927. Serial No. 234,809.

The invention relates to automobile signals, and has for its object to provide a device of this character by means of which an automobile may signal when it is going to 5 make a right turn or a left turn, and when it is going to stop or start. A further object is to provide a device of this character which may be read from either the front or the rear. A further object is to provide a 10 device of this character having two sets of rollers oppositely placed in the frame, and so marked that each set will spell a word visible in opposite directions when the rollers are in certain given positions. A further object is to provide a device of this character 15 in which a plurality of rollers are placed in a frame in two sets oppositely placed, each set of rollers being so marked that the marks collectively form words at given positions, and in which the rollers are all interconnected 20 by gears so that they may all be turned simultaneously and to the same extent, thereby displaying signal data observable by both an approaching and a following vehicle.

With the above and other objects in view, the invention resides in the combination and arrangement of parts as hereinafter set forth, shown in the drawing, described and claimed, it being understood that changes in the precise embodiment of the invention may be 30 made within the scope of what is claimed without departing from the spirit of the invention.

In the drawing:

Figure 1 is a side elevation of the device with the rollers in a position to spell "Stop".

Figure 2 is an end elevation of the device showing the gear connections between the rollers.

Figure 3 is a view of the indicating dial and operating handle.

Figure 4 is a view of the device with the rollers in a position to form "Go".

Figure 5 is a view of the device with the rollers in a position to form "Left".

Figure 6 is a view of the device with the rollers in a position to form "Right".

Figure 7 is a perspective view of a portion of some of the rollers showing how the rollers are marked.

Referring to the drawing, the numeral 1 designates a carrying frame which is adapted to be secured to the outer side 3 of an automobile. In the carrying frame 1 are placed 55 in their proper positions the rollers 2. The rollers are placed in the frame in two sets,

each set extending vertically in alignment in the frame and placed directly opposite the other set, and facing in the opposite direction from the other set so that the same signal data will be shown and may be read equally well from both the front and the rear. Secured to the outer end of each roller is a gear 4 which is in intermeshed connection with all the other like gears connected to the other rollers in the same set. Thus one roller cannot turn without all of the other rollers turning simultaneously to the same extent.

The rollers 2 are operated by means of the shaft 5 which extends between the spaced sets of the rollers and which has at its outer end a gear 6, which is intermeshed with adjacent gears of both sets of gears 4. The shaft 5 extends through the frame of the car into the interior of the car. On the end 75 of the shaft is disposed the handle 7, which can be handily operated from the drivers seat, and by means of which the driver of the car may operate the signal. The handle 7 is disposed adjacent to the inner face of an indicating dial 8 which is secured to the inner side 80 of the automobile body. This indicating dial in connection with which the handle 7 is used as a pointer has marked upon its face the same words, as "Stop", "Go", "Left", and "Right", which are indicated by the rollers. These words are marked upon the face of the dial in such a manner that when the handle 7 has been moved to the proper position to 85 indicate a given signal the rollers will display the corresponding signal on both sets of rollers observable by both an approaching and a following driver.

The rollers 2 are all so marked that each set will form a word at given positions of the rollers, and a plurality of rollers of each set have markings on a part only of the signal word, so that a plurality of roller markings cooperate to produce the signal word, and the markings are so arranged that each 90 degree revolution of the rollers displays a different signal, so that four different signals may be displayed. Thus in Figure 7, the numeral 9 designates the marks upon the rollers forming the upper part of the letter "S" in the indicating position. In the same figure the numeral 10 designates the marks which will form part of another letter when the rollers have been turned another 90 degrees, and so on for each 90 degree movement of the 95 rollers.

From the above it will be seen that an auto-

mobile signal is provided comprising a plurality of relatively small rollers cooperating to produce a relatively much larger signal word, whereby the device may be constructed 5 of a size which will not be objectionable as an accessory to an automobile, and which at the same time is simple of structure, and constituted of parts which will not easily wear or become inoperative.

10 The invention having been set forth what is claimed as new and useful is:

1. An automobile signalling device comprising a frame, oppositely disposed sets of rollers carried by said frame marked to collectively form words at given positions, driving connections between all the rollers for rotating the same in unison, and lever means for operating the rollers.

2. An automobile signalling device comprising a carrying frame, two oppositely facing, vertically disposed sets of rollers carried by said frame, both sets of said rollers being so marked that upon each turn of given extent each set of rollers collectively forms a word, gear connections between all of the rollers, an operating crank having connection with one of said gears, and an indicating dial, said crank being disposed adjacent said indicating dial.

3. An automobile signal having a carrying 30 frame, two oppositely disposed sets of rollers so marked that upon each given turn of the rollers a like word is formed on each set, and control means whereby the rollers of each set will be rotated in unison. 35

4. An automobile signal having a carrying frame, two sets of vertically disposed rollers carried by said frame, each set of said rollers being so marked that upon each given turn of the rollers in unison a word is formed that is 40 visible in front and rear, gear connections between the rollers of each set, an intermediate operating gear meshing with adjacent gears of both sets, and means for actuating said intermediate gear. 45

5. A signal device having a carrying frame, two oppositely disposed sets of aligned rollers carried by said frame, said rollers having markings which collectively in varying positions form a plurality of words, means for 50 operating the rollers of each set in unison, an indicating dial, and a pointer connected with said operating means and movable for rotating said rollers to form and display a given signal word. 55

In testimony whereof I affix my signature.

CLARENCE E. GOHEEN.
